UNITED STATES PATENT OFFICE

MORRIS J. ELSING, OF TUCSON, ARIZONA

METHOD OF MINING

Application filed March 3, 1931. Serial No. 519,820.

This invention relates to a method of mining. The general object of the invention is to provide a method which is both cheap and safe in its operation.

The new method includes some of the features of two other methods of mining, but in such a way as to become an entirely new method.

The improved method embraces one of the features of the shrinkage method and of the sub-level method, but the safety principle by which safety is secured in the improved method is present in neither the shrinkage method nor the sub-level method.

The improved method may be carried out in a number of different ways as shown in the accompanying drawings which illustrate four different ways in which the improved method can be carried out.

In these drawings:

Figure 1 is a vertical sectional view showing the sub-level method.

Fig. 2 is a similar view showing the second method of carrying out the invention in which the raises are parallel with the angle of repose of the broken ore.

Fig. 3 is a view showing a third way of carrying out the invention, in which the raises are normal to angle of repose of broken ore.

Fig. 4 is a view showing the fourth way of carrying out the invention.

Reference to the accompanying illustrations will show the method of operation.

Assume that the ore body to be mined is a more or less vertical vein, 20 feet wide, and that the walls are firm but that if large openings are made in the vein, the ore is apt to cave in rather large slabs. The only method by which such a vein could be mined is by one of the higher cost methods requiring timber support. This results in a high cost per ton.

My method can be applied to mining such an ore body as follows:—A raise 10 would be driven at some convenient distance from the point of the beginning of stoping, and from this raise at vertical intervals of, say 20 feet, intermediate or sublevel drifts 1, 2, 3, 4 will be driven in the vein to a point above the

proposed stope. A small opening is made over a chute 5 on the main level 6 in the customary way of making openings underground. The roof and walls of the small opening are then drilled and then drilling is done in the floor of the first sublevel drift immediately over this opening.

The holes in the opening are then blasted and blasting of the holes in the bottom of the sublevel drift follows. Holes have been so placed that the combined blasting will break the ore to the floor of the sublevel drift mentioned. In this way the ground between the top of the small opening at the chute and the bottom of the sublevel drift will be a mass of broken ore. Holes such as 7 are then drilled above the sublevel drift contiguous to the broken ore, and holes such as 8 will be drilled downward from sublevel number 2 to more or less meet those drilled up from sublevel number 1.

A certain amount of ore will then be drawn from the chute mentioned on the main haulage level, after which the holes mentioned on sublevel numbers 1 and 2 will be blasted. Only sufficient ore will be drawn from the chute to accommodate the ore to be broken by the next blasting. By similar successive steps the stope will arrive at the stage shown in Fig. 1.

Fig. 1 shows the stope filled with broken ore. The original drift has been enlarged to a size sufficiently large to allow the drilling of holes in all directions; sideways, as well as upwards and downwards. After drilling has been done on all sublevels a calculation is made regarding the amount of ore which will be broken by blasting the holes on each sublevel. Only that amount of broken ore is drawn from chute number 5' to make room for the additional ore to be blasted. The face of the broken ore will then assume approximately the position of the line A'—B'.

Blasting by electric firing may be done, and the holes below sublevel number 1 will be blasted first and followed by the holes below and above sublevel number 2, and so on to the highest sublevel. In this way the broken ore will fill the opening made by drawing of the ore.

The line A—B, the line of the unbroken ore, will be approximately parallel and coincident to the angle of repose of the broken ore so that the opening after ore is drawn will be 5 more or less of a uniform size, and only sufficiently large to accommodate the new ore to be broken. Repeated incline slices will thus be taken off the ore body. As the stope advances ore may be drawn from chute members 10 5" and later from chute number 5a; but only such an amount of ore will be removed as will not draw the ore from along the working face A—B. As mining and drawing continue, there will always be a pyramid of 15 broken ore as a support for the working face of unbroken ore.

In mining of wide veins or ore deposits transverse cross cuts from the sublevel drifts, or in some cases, benches, will be driven parallel to the face of ore to be broken; and from 20 these the drilling will be done.

The most important advantage of my method is that it combines safety with cheapness of operation. It never requires that 25 men go into large unsupported openings. Drilling is always done in small openings in unbroken ground which is supported by broken ore. Large caves of ground are impossible.

It is possible to use my method in ground which cannot be worked by the old shrinkage method of stoping, or by the sublevel stoping method. This applies to hard 30 ground which is treacherous in the sense that 35 large blocks, slabs or boulders may cave, as well as to soft ground which will not stand open over the usual width required in shrinkage stoping.

At all times the working face is close to 40 the miner so that careful inspection is possible.

My method is applicable to mining narrow and wide veins, or small or large deposits. It can be used in mining large pillars left between stopes and as an auxiliary 45 method in caving. It can be applied in bringing down a block of ground in the caving method which has been insufficiently undercut and does not cave.

It has the advantage of the low cost with 50 safety. Little or no timber is required. In case of hard ore or soft ore containing hard boulders, instead of chutes, bulldozing chambers and grizzlies will be provided.

My method can be applied with a minimum 55 number of pillars.

The principle of my method is different from the sublevel method in that the ore being drilled is supported. This is equally 60 true when compared with shrinkage stoping.

It is also different from shrinkage in that in shrinkage mining horizontal layers are taken out and such advance is vertically upwards. In my method layers are inclined and progress is horizontally.

In my method there is a certain flexibility of operation. It is not confined to the breaking of ore as shown in Fig. 1. Ore may be broken through the means of sublevel drifts as shown in Fig. 1, or from inclined raises 70 as shown in Fig. 2, or from inclined raises which may be at right angles to the face of ore being broken as shown in Fig. 3 or from a single subdrift with the drilling of deep 75 drill holes, as shown in Fig. 4.

My method is not confined to the drilling by ordinary machine drills. In some cases drilling may be done with the so-called deep drilling machine with sectional drill steel. In other cases, drilling may be done with 80 diamond drills.

Under certain ground conditions my method will permit the maintaining of a small opening between the broken ore and parts of the working face. This will be advantageous 85 especially in working the wider deposits of harder ore. This opening need not be more than a few feet wide. In such a case, all of the working face is not provided with support, but if immediate support is necessary, 90 the blasting of a few holes will fill the opening. With the small opening, no serious caving can occur.

Another feature of my method which at 95 times might vary is that the working face of solid ore will not always be parallel to the angle of repose of the broken ore.

Under certain conditions drill holes will not be put in parallel to the face of the ore being broken. These holes may be vertically 100 upward and downward, in which case after blasting a section of the working face would have an inverted step-like appearance.

The working of my method does not require 105 the blasting of all drill holes on the different sublevels at one time. In cases where it is desirable and possible to maintain a small opening between the working face of solid ore and the face of the broken ore drilling may be done on the lower sublevel, and after 110 blasting, drilling may be done on the next higher level. In this way support will always be provided for the ore below the driller as drilling is done on successively higher levels.

The method may also be carried out by removing the broken ore from the stope and placing waste material therein which waste material must of course, be arranged with an inclined face to parallel the face of the stope, 115 as before set forth. This waste material may be introduced into the stope by dropping it down through a raise, such as 10 and which has its lower end in communication with the stope.

As the stope increases in size and the pile 120 of waste material advances other raises may be formed for the introduction of the material so as to keep the inclined face of the pile 125 adjacent to the face of the stope. The broken

ore is removed from the chutes 5 as before. This material may entirely fill the stope while the drilling is being done and then sufficient of the material is removed to form 5 a space for receiving the ore to be blasted.

Having thus described my invention, what I claim as new is:—

1. The herein described method of mining comprising the breaking of ore in inclined layers parallel to the angle of repose of the broken ore, by drilling and blasting from within the ore body itself and not from below it, and the removing of the broken ore from chutes on the level below in such 10 a way that the ore remaining in the stope will be parallel to the face of the next layer to be mined.
2. The herein described method of mining comprising the breaking of ore in inclined 20 layers parallel to the angle of repose of the broken ore, by drilling and blasting from within the ore body and not from below it, and the removing of only sufficient broken ore to make room to accommodate the ore to 25 be broken in blasting the next layer, after which blasting, the broken ore fills the opening and becomes the support for the next layer while it is being drilled.
3. The herein described method of mining 30 comprising the breaking of ore in inclined layers parallel to the angle of repose of the broken ore, by drilling and blasting from within the ore body itself and not from below it, and the removing of broken ore to 35 make more room than is sufficient to accommodate the ore to be broken in blasting the next layer, after which blasting the broken ore assumes a face substantially parallel to the face of the broken ore and a few feet 40 from it.
4. The herein described method of mining comprising the breaking of ore in inclined layers parallel to the angle of repose of the broken ore, by drilling and blasting from 45 within the ore body itself and not below it, and removing all of the broken ore and filling the open stope with waste so that there will be an inclined opening parallel to the face of the ore to be broken into which opening ore will be blasted and then drawn from 50 the stope.
5. The herein described method of mining comprising the breaking of ore in inclined layers parallel to the angle of repose of the broken ore by drilling and blasting from 55 within the ore body itself and not from below it, and removing all of the broken ore and filling the open stope with waste which will act as a support for the ore while being drilled after which sufficient waste will be 60 drawn to accommodate the ore to be blasted.

In testimony whereof I affix my signature.
MORRIS J. ELSING.
